UNITED STATES PATENT OFFICE.

JOHN J. GRANT, OF NEW YORK, N. Y.

BALL-GRINDING MACHINE.

1,357,044.

Specification of Letters Patent. Patented Oct. 26, 1920.

Application filed October 31, 1919. Serial No. 334,686.

To all whom it may concern:

Be it known that I, JOHN J. GRANT, a citizen of the United States, resident of New York, county of New York, and State of New York, have invented new and useful Improvements in Ball-Grinding Machines, of which the following is a specification, the principle of the invention being herein explained and the best mode in which I have 5 contemplated applying that principle, so as to distinguish it from other inventions.

My invention relates to ball grinding machines, commonly referred to as "dry grinders," its object being to provide a machine of this character which will be simple and economical in its construction and operation. The said invention consists of means hereinafter fully set forth and particularly pointed out in the claims.

20 The annexed drawings and the following description set forth in detail certain mechanism embodying my invention, the disclosed means, however, constituting but one of various mechanical forms in which the principle of the invention may be applied.

In said annexed drawings:

Figure 1 is a side elevation of the machine embodying my invention.

30 Fig. 2 is an elevation of the machine taken in the direction indicated by the arrow 1 in Fig. 1.

Fig. 3 is a vertical axial section taken upon the plane indicated by line III—III of Fig. 2, looking in the direction indicated by the arrows 2 in said figure.

Fig. 4 is a fragmentary axial section of the upper part of the machine taken upon the plane indicated by line IV—IV of Fig. 1.

40 Fig. 5 is a horizontal section taken upon the plane indicated by line V—V in Fig. 3.

Fig. 6 is a fragmentary plan of the upper part of the machine with the grinding wheel removed so as to disclose the construction and location of the ball race.

Fig. 7 is a detail section taken upon the plane indicated by line VII—VII of Fig. 6.

50 Figs. 8 and 9 are detail sections of bearings, upon an enlarged scale.

Fig. 10 is a fragmentary plan of the grinding wheel-carrying disk.

Fig. 11 is a detail section taken upon the plane indicated by line XI—XI of Fig. 10.

55 The pedestal A of the machine, Figs. 1, 2 and 3, is formed with a vertical centrally

located pillar A', whose outer surface is cylindrical and forms a journal for a hollow sleeve B rotatable thereon. Below the lower end of the sleeve B is mounted an auxiliary sleeve B'. A ball bearing b is interposed between the lower extremity of the sleeve B and the upper end of sleeve B' forming a thrust bearing for these two parts, as will be readily understood. A circumferential annular groove b' is formed near the upper portion of the auxiliary sleeve B' into which project two pins c c fixed in the ends of the two arms of a bifurcated yoke C. This yoke is fixedly secured to an oscillatory shaft C' which is mounted in bearings formed in lugs d d which form integral parts of an outer housing D. Secured upon the outer end of the shaft C' is a hand lever C², by means of which the shaft may be oscillated. Fixed upon said shaft intermediately of the hand lever and the adjacent lug d is an arm C³ formed with a segment c', to the upper portion of which is secured a flexible metal strap c², as shown in Figs. 3 and 5. The lower end of the strap is provided with a hook c³ which engages the upper end of the helical spring c⁴, the lower end of which latter is secured to a vertically mounted rod c⁵ the lower end of which is threaded into a post a forming an integral part of the pedestal A. The connection between the rod c⁵ and spring c⁴ is such that the rod may be rotated in the lower end of the spring so that the tension of the latter may be adjusted by screwing the rod into or out of the post a, as will be readily understood. The arm C³ is provided with an auxiliary arm c⁶ formed with shoulders c⁷ and c⁸, which may be engaged by a lug e formed on a second hand or locking lever E, shown in Fig. 3 and in dotted lines in Fig. 5. This locking lever is suitably fulcrumed upon the housing D, and retains the hand lever C² and hence the yoke C and sleeve B' in position against the action of the spring c⁴, as will be hereinafter described. The tension of this spring is made such as to overcome the weights of the sleeves B and B' and their attached parts, so that their tendency is to move upwardly, as a result of such tension. The upper portion of the sleeve B is formed with a flange b² on the outer edge of which is secured an annular ring b³ forming the bottom of a ball race, as will further appear. Upon the lower end of the

sleeve B is shrunk a gear b^4 , which meshes with an elongated pinion F. This pinion is fixed to a vertical shaft F', as shown in Figs. 3 and 5, mounted in suitable bearings 5 formed in the housing D. Upon the lower end of this shaft is a gear f which meshes with a pinion g, which latter is fixed to a rotatable hollow sleeve g' mounted in a suitable bearing a' in the pillar A. The lower 10 end of this sleeve is provided with a bevel gear g² which meshes with a second bevel gear g³ fixed to a horizontal driving shaft G, the latter mounted in a suitable bearing a² formed in the base A as shown. A suitable 15 driving pulley G' is mounted upon the shaft G.

It will therefore be seen that the rotation of shaft G will effect the rotation of shaft F', the rotation of which latter drives the 20 sleeve B through the medium of the pinion F and gear b⁴. The elongation of pinion F permits a limited vertical movement of the sleeve while it is being driven, as will be readily understood.

25 Passing through the sleeve g' and keyed thereto is a vertical driving spindle H, whose axis is eccentric relatively to the axis of the pillar A. A suitable bearing a³ is formed in the upper part of the pillar for 30 the upper part of this spindle, as shown in Figs. 3 and 4. To the upper part of this spindle is secured a disk H' to whose lower surface is secured the annular grinding wheel H², the latter having its axis concentric with that of the spindle H and therefore eccentric relatively to the sleeve B, flange b² and annular ring b³.

The lower end of the spindle H rests upon a thrust bearing h' mounted upon the upper 40 end of a rack h², as shown in detail in Fig. 8. This rack is slidably mounted in a suitable guide a⁴ formed in the base A, and engages a toothed segment h³ which is fixed to the oscillatory shaft h⁴ mounted in suitable 45 bearings in the pedestal. The outer end of this shaft has fixed upon it a worm wheel h⁵, Fig. 1. This worm wheel is engaged and operated by a worm h⁶ mounted upon a shaft h⁷ whose upper end is connected with a hand wheel H³ through the 50 medium of bevel gears h⁸ and h⁹, as shown in detail in Fig. 4. This hand wheel is fixed to a suitable spindle h¹⁰ mounted in the housing D as shown.

55 Rotation of the hand wheel H³ will therefore rotate the shaft h⁷ and hence the gear h⁵. The oscillation of the segment h³ effects raising and lowering of the spindle H and therefore the grinding wheel H², as will be 60 readily understood.

To the upper end of the pillar A' is secured a disk A², the outer edge of which is beveled as shown to overhang slightly. Upon the upper edge of this disk is fixedly 65 secured a hardened steel ring a⁵, Fig. 6,

which forms the inner side of a ball race. Forming part of the housing D and surrounding the disk A² to form an annular open space, is an annular ring D', whose inner edge is beveled to overhang, as shown. 70 Upon the upper surface and at the inner edge of this disk is secured a hardened steel ring j which forms the outer edge of the ball race.

Secured upon the under surface of the 75 disk A² is a flange A³ projecting outwardly toward the annular ring b³ of less diameter than the exterior diameter of the latter, and inclined downwardly to form a guard, the purpose of which will be hereinafter fully 80 described.

That part of the housing D immediately below the annular disk D' is made substantially vertical to form a web D². This web is formed with a plurality of circumferentially placed openings d' d', Figs. 2 and 3, of sufficient area to permit balls of any size which are ground on the machine, to pass therethrough. Adjacent to the lower portion of these openings and extending partly 90 upon the inside of the housing D and partly upon the outside is a trough d² which passes circumferentially around the housing and inclines downwardly from one side to the other, the lowermost portion terminating in 95 an opening d³ through which the balls may drop.

A portion of the disk D' is extended as at d⁴. This part is formed with a slide-way in which is located a slide d⁵ provided with a 100 hand knob d⁶. The inner edge of this slide carries a segment j' of the hardened ring j, as shown in Fig. 6. A set screw d⁷ is provided in the side of the extension d⁴ whereby the slide d⁵ may be fixed in position when 105 the machine is in operation. For convenience, I have formed the upper surface of the ring D' separately in the form of a removable ring, as shown. By this means, that portion of the ring carrying the hardened race j may be readily removed if desired. 110

The above described device operates as follows:

Assuming that the ball race is empty 115 and it is desired to fill same with the rough balls to be ground, the set screw d⁷ is loosened and the slide pulled back as shown in dotted lines in Fig. 6. Hand lever C² is now manually manipulated so as to 120 bring the shoulder c⁷ into engagement with the lug e on the lever E, as shown in dotted lines in Fig. 3 and in full lines in Fig. 1. This brings the annular ring b³ into a position such as to constrict the ball race sufficiently to prevent the balls from dropping into the trough d². The rough balls are now fed into the race in the desired quantity, whereupon the slide d⁵ is replaced and fixed in position. The hand lever E is now 130

raised out of engagement with the arm c^6 and then released, whereby the spring c^4 is given free play to raise the sleeve B upwardly and thus press the balls up against the rings j and a^5 . The machine is now 5 started running, so as to revolve the grinding wheel H^2 . The lower exposed grinding surface of this wheel may now be brought downwardly into contact with the upper exposed surfaces of the balls by turning the 10 hand wheel H^3 in the proper direction. This hand wheel H^3 is suitably graduated so as to indicate the position of the grinding wheel, as will be readily understood. 15 As the grinding operation continues and the diameter of the balls decreases, the spring c^4 moves the sleeve upwardly to compensate therefor and the hand-wheel H^3 is turned to lower the grinding wheel to compensate for the wear of the latter. 20

When the grinding operation is completed and it is desired to discharge the balls from the race, the lever C^2 is raised until the lug e of the lever E engages the shoulder c^8 of the 25 arm c^6 , as shown in dotted lines in Fig. 3. This movement lowers the ring b^3 so as to allow the balls to drop in the trough d^2 through the openings d^7 , the flange A^3 during this action preventing the balls from 30 dropping upon the inside of said ring b^3 .

The disk H' is provided with a plurality of sectoral openings h^{11} , Figs. 4 and 10. The corresponding edges of these openings are inclined as shown in dotted lines at h^{12} 35 in Fig. 10, and to these inclined surfaces are secured vanes H^4 . The inclination of these vanes is such that when the disk and grinding wheel are rotated in the direction indicated by the arrow in said Fig. 10, a 40 current of air will be created from the interior of the grinding wheel to the exterior thereof. The dust formed in the grinding operation will therefore be drawn into the interior of the grinding wheel and upwardly 45 through the openings h^{11} , thereby contributing to the comfort and safety of the grinding operator.

What I claim is:

1. In a ball-grinding machine, the combination of a suitable support; a grinding wheel rotatably mounted thereon and having a vertical axis; and a ball race beneath said grinding wheel, having a vertical axis eccentrically located relatively to said wheel's axis; said race comprising a fixed inner disk and a fixed outer ring forming an annular space and the sides of the race, together with a vertically movable and spring-actuated rotatable ring forming the bottom of such race. 50
2. In a ball-grinding machine, the combination of a suitable support; a vertically movable grinding wheel rotatably mounted thereon having a vertical axis and a lower face exposed to form a grinding surface; a 55
3. In a ball-grinding machine, the combination of a suitable support including a vertical hollow pillar forming a cylindrical journal; a spindle mounted in said pillar and passing through the hollow portion thereof, the axis of such spindle being eccentric relatively to the axis of said journal and parallel therewith; a grinding wheel secured to the upper end of said spindle and having a lower face exposed to form a grinding surface; an inner disk secured to said pillar, and an outer ring mounted upon 60 said support; said inner disk and outer ring forming the sides of a ball race and an intermediate annular space; a sleeve rotatably mounted on said journal and having an annular ring mounted thereon forming the bottom of said race. 65

ball race beneath said grinding wheel having a vertical axis eccentrically located relatively to said wheel's axis; said race comprising a fixed inner disk and a fixed outer ring forming an annular space and the sides 70 of the race, together with a vertically movable and spring-actuated rotatable ring forming the bottom of such race.

3. In a ball-grinding machine, the combination of a suitable support including a vertical hollow pillar forming a cylindrical journal; a spindle mounted in said pillar and passing through the hollow portion thereof, the axis of such spindle being eccentric relatively to the axis of said journal 75 and parallel therewith; a grinding wheel secured to the upper end of said spindle and having a lower face exposed to form a grinding surface; an inner disk secured to said pillar, and an outer ring mounted upon said support; said inner disk and outer ring forming the sides of a ball race and an intermediate annular space; a sleeve rotatably mounted on said journal and having an annular ring mounted thereon forming the 80 bottom of said race.

4. In a ball-grinding machine, the combination of an inner disk and an outer ring together forming an annular space and the slides of a ball-race; an annular ring forming the bottom of such race; and a flange 95 on the said inner disk and projecting toward said annular ring.

5. In a ball-grinding machine, the combination of an inner disk and an outer ring 100 forming an annular space and the sides of a horizontal ball race; a rotatable annular ring having a vertical axis and movable in the direction of said axis, forming the bottom of said race; and a downwardly inclined flange mounted upon the lower surface of said inner disk and projecting outwardly toward said annular ring. 105

6. In a ball-grinding machine, the combination of a suitable support formed with an inner stationary disk and an outer stationary ring forming an annular space and the sides of a horizontal ball race and furthermore formed with an annular tray below and adjacent to said race; and an annular 110 rotatable ring forming the bottom of said race having a vertical axis and movable in the direction thereof. 115

7. In a ball-grinding machine, the combination of a support provided with an outer portion provided with a ring forming the outer side of a horizontal ball race and an inner portion formed with a disk forming the inner side of such ball race; an intermediate member provided with an annular ring forming the bottom of said ball race, said intermediate member being rotatably mounted upon a vertical axis and movable in the direction thereof; said outer portion of the support being provided with 120 125 130

an annular tray below and adjacent to said ball race and with a series of apertures establishing communication between said race and said tray; and an outwardly and downwardly projecting inclined ring secured to the lower surface of said inner disk.

8. In a ball-grinding machine, the combination of a rotatably mounted grinding wheel; a ball race adjacent thereto and including a member adapted to move toward or from said wheel; yielding means tending to actuate said movable member toward said wheel; and means for fixing said yielding means in various positions.

15 9. In a ball-grinding machine, the combination of a rotatably mounted grinding

wheel; a ball race adjacent to said wheel and including a member movable toward and from said wheel; spring-actuated mechanism connected with said movable member and adapted to actuate same toward said wheel, and including a manually operable lever; and a manually operable locking lever adapted to engage said spring-actuated mechanism to hold same in various positions, whereby said movable member may be held in various positions. 20 25

Signed by me this 4th day of October, 1919.

JOHN J. GRANT.
